(57) CLAIM

The ornamental design for a basketball shooting teaching device, as shown and described.

DESCRIPTION

FIG. 1 is a front elevation view showing my new design for basketball shooting teaching device;

FIG. 2 is a rear elevation view thereof;

FIG. 3 is a right side elevation view thereof, the left side elevation being identical thereto;

FIG. 4 is a top plan view thereof; and,

FIG. 5 is a bottom plan view thereof.

The broken lines showing the backboard and basket are shown for illustrative purposes only and form no part of the claimed design.
